COMBINATION TOILET SEAT AND VENTILATOR

Gustave Meyer, 956 Santa Fe Drive,
Denver, Colo. 80204

Filed Apr. 11, 1968, Ser. No. 11,420

Term of patent 14 years

Int. Cl. D23—02

U.S. Cl. D23—71

FIG. 1.

FIG. 2.

FIG. 3.

FIG. 1 is a top plan view of a combination toilet seat and ventilator showing my new design;

FIG. 2 is a side elevational view thereof; and

FIG. 3 is a cross-section taken on the line 3—3, FIG. 2.

I claim:

The ornamental design for a combination toilet seat and ventilator, as shown.
